AIR HAMMER TOOL PIECE

George O. Fortenberry, 6323 Moonglow Drive,
Dallas, Tex. 75241

Filed Apr. 13, 1965, Ser. No. 84,759

Term of patent 14 years

(Cl. D54—14)

FIG. I is a perspective view of an air hammer tool piece showing my new design;

FIGURE II is a top plan view thereof;

FIGURE III is a side elevational view thereof;

FIGURE IV is a bottom plan view thereof;

FIGURE V is a front end view thereof; and

FIGURE VI is a rear end view thereof.

I claim:

The ornamental design for an air hammer tool piece, substantially as shown.
